(57) **CLAIM**

The ornamental design for an inhaler, as shown and described.

DESCRIPTION

- 1.1** : Right
- 1.2** : Left
- 1.3** : Front
- 1.4** : Back
- 1.5** : Top
- 1.6** : Bottom
- 1.7** : Perspective

The dash-dash broken lines represent portions of the inhaler and form no part of the claimed design. The dash-dot broken lines represent a boundary between claimed and unclaimed subject matter and form no part of the claimed design.
